DESIGN FOR A SOAP DISH

Joseph Bozoti, Parma, Ohio

Application March 25, 1947, Serial No. 137,852

Term of patent 7 years

(Cl. D4—3)

To all whom it may concern:

Be it known that I, Joseph Bozoti, a citizen of the United States and a resident of Parma, in the county of Cuyahoga and State of Ohio, have invented a new, original, and ornamental Design for Soap Dish, of which the following is a specification, reference being had to the accompanying drawing, forming a part thereof, wherein

Fig. 1 is a top plan view of a soap dish embodying my new design;

Fig. 2 is a side elevation thereof; and

Fig. 3 is a transverse section taken on the line 3—3 of Fig. 1.

I claim:

The ornamental design for a soap dish, as shown and described.

JOSEPH BOZOTI.
